E. C. RUDKIN

PUNCHING DIE

Filed Aug. 4, 1922

Inventor:
Edwin C. Rudkin

by Night & Son, Quincy, Mass. Atlys.

UNITED STATES PATENT OFFICE.

EDWIN C. RUDKIN, OF BROCKTON, MASSACHUSETTS, ASSIGNOR TO NORMAN L. BROCK, OF WEST BRIDGEWATER, MASSACHUSETTS, JOSEPH C. KNIGHT, OF BROCKTON, MASSACHUSETTS, AND EDMOND A. HEBERT, OF HOLBROOK, MASSACHUSETTS.

PUNCHING DIE.

Application filed August 4, 1922. Serial No. 579,664.

To all whom it may concern:

Be it known that I, EDWIN C. RUDKIN, a citizen of the United States, residing at Brockton, in the county of Plymouth and State of Massachusetts, have invented new and useful Improvements in Punching Dies, of which the following is a specification.

This invention relates to a punching die, constituting an element of a machine for ornamenting blanks forming parts of shoe uppers, etc., by cutting small holes therein, arranged in a series extending along edge portions of the blanks, the die including a die plate bearing on a bed plate or holder, adapted to be horizontally supported on the bed of the machine, the die plate being provided with an elongated row or series of upstanding punches, formed and arranged to ornament an edge portion of a blank deposited on a yielding apertured stripper plate normally supported slightly above the cutting edges of the punches, the blank being pressed against the punches by a reciprocating presser or platen, which depresses the stripper plate and causes the punches to cut holes in the blank.

It is often desirable to additionally ornament the central portion of the blank, by forming holes in its central portion, within the row or series of holes formed by the elongated row of punches.

One object of the invention is to enable the plate of a punching die, which may be called a primary die, carrying a row of blank edge-ornamenting punches, to locate the plate of a supplemental punching die with its punches in position to ornament the central portion of the blank within the row of holes formed by the punches of the primary die, the latter being adapted to be used independently when additional ornamentation is not desired.

Another object is to provide a bed plate or holder, adapted to simultaneously support a primary and a secondary punching die, and to permit either the conjoint use of said dies, or the use of the primary die alone.

Another object is to provide means for supporting a primary and a secondary punching die in fixed adjustable relation to each other, so that the distance between the punches of the two dies may be varied. I

attain these and other objects by the improved construction hereinafter described and claimed.

Of the accompanying drawings forming a part of this specification,—

Figure 1 is a perspective view of a primary die, constructed in accordance with the invention, a portion of the stripper plate being removed;

Fig. 2 is a perspective view of a secondary die, adapted to cooperate with the primary die, the stripper plate of the secondary die being removed;

Figs. 3 and 4 show in perspective the parts or sections of a sectional bed plate or holder, adapted to support the primary and secondary dies, and hold said dies operatively related to each other;

Fig. 5 is a top plan view of a punching machine element which includes the punching dies and the sectional holder shown by the preceding figures, portions of the stripper plates of the punching dies being broken away;

Fig. 6 is a section on line 6—6 of Fig. 5;

Fig. 7 is a section on line 7—7 of Fig. 5;

and

Fig. 8 is a perspective view, showing a modified form of the bed plate or holder.

The same reference characters indicate the same parts in all of the figures.

The drawings show the preferred embodiment of the invention, but I wish it understood that various changes and modifications may be made, within the scope of the appended claims.

The primary die, shown separately by Figure 1, comprises a plate 12, which may be composed of rigidly connected layers, and has a continuous forward edge portion, provided with the usual upstanding tubular punches 13, which may be of any desired form, and may have any desired arrangement, whereby an elongated row or series is formed. In this instance, some of the punches are larger than the others. The plate 12 is provided with a throat extending forward from its rear edge, and preferably of the form shown by Figure 1, the throat having parallel side faces 14, and its closed end being formed by angular faces

15, forming a re-entrant angle, the apex of

which is in close proximity to the central punches 13.

The stripper plate 16 of the primary die is attached at its rear edge, as by screws 17, 5 to the rear edge portion of the plate 12, its free edge portion being provided with the usual punch-receiving holes 18, and yieldingly supported as usual, so that the upper surface of its free edge portion is 10 substantially flush with the upper ends of the punches. The stripper plate has a throat coinciding with the throat of the plate 12, and having side faces 19, and angular end faces 20.

15 The secondary die shown separately by Figure 2, comprises a plate 21, which may also be composed of rigidly connected layers, and has parallel edge faces 22, and angular end faces 23, conforming to the faces 20 of the throat in the plate 12. The plate 21 is provided at its angular end portion with a group of upstanding tubular punches 24, having any desired form and arrangement. The insertion of the plate of the secondary 25 die in the throat of the primary die locates the secondary die punches 24, in position to cooperate with the primary die punches 13, in ornamenting a blank 25, indicated by dotted lines in Figure 5, the punches 24 30 forming holes in the central portion of the blank within the row of holes formed by the punches 13. The secondary die plate is provided with a yielding stripper plate 26, conforming to the outline of said die plate, the 35 blank 25 being supported by the two stripper plates before the punching operation.

It is customary to superimpose the punch-carrying plate of the punching die of a blank-ornamenting machine, on a bed-plate 40 or holder, adapted to rest loosely on a fixed part of the machine, said bed-plate having channels coinciding with the punches, and receiving and conducting away the cuttings detached from blanks by the punches, means 45 being provided for detachably connecting the die-plate with the bed-plate, with the bores of the punches registering with the channels in the bed-plate. In accordance with my invention, I provide a bed-plate 50 adapted to detachably engage and support both the primary die and the secondary die, and permit the primary die to be used either alone, or with the secondary die.

Said bed-plate is preferably of sectional 55 construction, as shown by Figures 3 and 4, and includes a primary section 28, the area of which is similar to that of the primary die-plate 12, and a secondary section 29, the area of which is similar to that of the secondary die-plate. The primary section 28 has a throat with parallel side faces 30, angular end faces 31, and channels 32 arranged to coincide with the punches 13. The secondary section 29 has parallel side faces 60 33, angular end faces 34, and channels 35

arranged to coincide with the punches 24, the secondary section being formed to enter the throat of the primary section.

The means for detachably connecting the die-plates with the holder sections may be 70 embodied in steady pins or dowels 36, fixed to and projecting downward from the die-plates, and sockets 37, formed in the holder sections and receiving said pins, as shown by Figure 7. The die-plates may be positively secured to the holder sections, after the insertion of the pins in the sockets, by screws 38. The secondary holder section 29 may be engaged with the primary section 28, by any suitable confining means adapted to 80 prevent accidental movement or displacement of the secondary section, said means as here shown, being adapted also to adjust the secondary section, and hold the same and the secondary punching die engaged therewith, with the punches 24 at different distances from the punches 13. To these ends the secondary section 29 is provided with an ear 40, having a slot 41, engaging the peripherally grooved head 42 of a screw 43 85 '90 which engages a tapped orifice 44 (Figure 3) in the primary section 28. Rotation of said screw causes it to move endwise, and move the secondary section endwise in the throat of the primary section. The plate 21 of the secondary die, and the throat of the primary die are preferably wider than the secondary holder section 29, and the throat of the primary section, so that the longitudinal edges of the plate 21 overlap 95 portions of the upper surface of the primary holder section, as shown by Figure 7.

If desired, the faces 30 of the throat of the primary section 28, may be grooved to receive tongues on the faces 33 of the secondary section 29.

The construction of the bed plate or holder may be modified, as shown by Figure 8, which shows a holder 46 without a throat, and forming a continuous support for the primary and secondary punching dies, said holder having sockets 37^a, to receive the steady pins on the primary die-plate, and sockets 37^b, to receive the steady pins on the secondary die-plate. The holder thus formed may have the channels 32 coinciding with the punches 13. The channels 35 coinciding with the punches 24 may be formed in a block 47, removably inserted in an opening 48 formed in the holder 46. 110 Another block having a different arrangement of channels corresponding with a different arrangement of punches 35, may be substituted for the block 47.

It will now be seen that I have provided 115 a punching machine element, which is adapted for use in ordinary punching machines for forming either one row or group of holes at a time, or two groups simultaneously, and that each of the primary and secondary 120

punching dies forming component parts of said element, may be used with other dies having different arrangements of punches.

It will be seen that I have provided a 5 punching machine element which includes a plurality of punching dies, adapted to be used either singly or simultaneously, each die having any suitable arrangement or grouping of punches, and a holder for said 10 dies, adapted to support the dies either separately, for independent use, or simultaneously, for conjoint use, the holder having outlets for cuttings formed by the die punches, and the dies and holder being provided with means whereby the dies may be 15 detachably secured to the holder in operative relation to each other.

I am, therefore, enabled to employ any 20 number of dies interchangeably, and to provide for each die a holder which is interchangeable with other holders, it being understood that each holder will have outlets 25 for the cuttings, arranged in conformity to a given arrangement of the die punches, so that, in changing from one arrangement of punches to a different arrangement, a holder having a corresponding arrangement of outlets will be employed. Any number of 30 interchangeable dies and interchangeable 35 holders fitting the dies, may, therefore, be provided for use in an ordinary punching machine.

I claim:

1. A punching-machine element comprising 40 a primary punching die including a die-plate and a group of tubular punches thereon in fixed relation to each other and to the plate and arranged to ornament an edge portion of a blank, the plate of the primary 45 die being provided with means for locating the plate of a secondary punching die with its punches in position to ornament another portion of the blank.

2. A punching-machine element comprising 50 a primary punching die including a die-plate, and a group of tubular punches thereon in fixed relation to each other and to the plate and arranged to ornament an edge portion of a blank, said plate having 55 a throat; and a secondary punching die including a plate insertible in said throat, and a group of tubular punches thereon in fixed relation to each other and to the plate, the throat being arranged to locate the plate 60 of the secondary die in position to ornament another portion of the blank.

3. A punching-machine element comprising 65 a primary punching-die including a die-plate, and a group of tubular punches thereon in fixed relation to each other and to the plate, and arranged to ornament an edge portion of a blank, said plate having a throat; and a secondary punching-die including a plate insertible in said throat, and 70 a group of tubular punches thereon in fixed

relation to each other and to the plate, the throat being arranged to locate the plate of the secondary die in position to ornament another portion of the blank, means being provided for holding said dies in a fixed 70 relation to each other.

4. A punching-machine element comprising 75 a primary punching die including a die-plate, and punches thereon, arranged to ornament an edge portion of a blank, said plate having a throat; and a secondary die including a plate insertible in said throat, and punches thereon, the throat being arranged to locate the plate of the secondary die in position to ornament another portion 80 of the blank, means being provided for adjustably holding said dies in a fixed relation to each other.

5. A punching-machine element comprising 85 a primary punching die including a die-plate, and punches thereon, arranged to ornament an edge portion of a blank, said plate having a throat; a secondary die including a plate insertible in said throat, and punches thereon, the throat being arranged to locate the plate of the secondary die in position to ornament another portion of the blank, and a holder on which said die plates are separately mounted and maintained in operative relation to each other, 90 said holder and plates having separable interengaging means.

6. A perforating-machine element substantially as specified by claim 5, said holder being provided with means for adjusting the secondary die to vary the distance of 100 its punches from those of the primary die.

7. A punching-machine element comprising 105 a primary punching die including a die-plate, and punches thereon, arranged to ornament an edge portion of a blank, said plate having a throat; a secondary die including a plate insertible in said throat, and punches thereon, the throat being arranged to locate the plate of the secondary die in position to ornament another portion 110 of the blank, and a sectional holder composed of a primary section conforming to the primary die-plate, and provided with a throat, and a secondary section conforming to the secondary die-plate, and insertible in the throat of the primary section, the die plates and holder being provided with separable interengaging means.

8. A perforating-machine element substantially as specified by claim 7, the said secondary section being adjustable in the throat of the primary section, means being provided for confining the secondary section in any position to which it may be 115 adjusted.

9. A punching-machine element comprising 120 a primary punching die, including a die-plate having a throat closed at one end, punches arranged in a row extending beside 125

the closed end of the throat, and a yielding stripper plate, adapted to cooperate with said punches, and having a throat registering with the throat of the die-plate; and a 5 secondary punching die, including a die-plate, punches arranged in a group at one end portion of said plate, and a yielding stripper plate adapted to cooperate with the last-named punches, the die-plate and stripper plate of the secondary die being formed to enter the throats of the primary die and its stripper plate.

In testimony whereof I have affixed my signature.

EDWIN C. RUDKIN.
